UNITED STATES PATENT OFFICE

JOHN W. HOOD, OF SALEM, VIRGINIA

COMBINATION TIE PLATE AND RAIL GRIPPER

Application filed May 29, 1930. Serial No. 457,130.

This invention relates to a combined tie plate and rail chair, and one object of the invention is to provide a device of this character which will serve very effectively as a tie plate and also as means for supporting a rail and firmly holding the rail in a set position when in place.

Another object of the invention is to so construct the improved rail chair and tie plate that when it is in use a rail will be firmly braced against outward thrust by the wheels of a car and prevented from turning over and thereby prevent danger of a wreck due to spreading rails.

Another object of the invention is to provide the rail plate with a wedge serving to firmly brace the base of a rail against transverse movement upon the plate and so form this wedge that when spikes are driven through spike-receiving openings in the wedge and plate and driven into a tie the wedge will be properly held in place and the spikes prevented from working loose.

Another object of the invention is to so form the plate and its cooperating wedge that when the device is in use rails will be very firmly gripped. This prevents the rail from creeping and also prevents longitudinal distortion of the rails.

Another object of the invention is to provide a device of this character so constructed that a rail may be very easily set in place or removed but cannot accidentally slip out of proper engagement with the rail chair or plate when secured thereon and further to prevent danger of spikes becoming cut and weakened near their heads by side edges of a rail base.

The invention is illustrated in the accompanying drawings, wherein

Figure 1 is a perspective view of the improved rail plate, a rail resting thereon being indicated by dotted lines,

Fig. 2 is a sectional view taken transversely through the rail and rail plate and showing the manner in which the plate is firmly secured upon a tie,

Fig. 3 is a sectional view taken longitudinally through the wedge and the portion of the tie plate upon which it rests.

Fig. 4 is a bottom plan view of the tie plate,

Fig. 5 is a perspective view of the wedge looking at the under face thereof,

Fig. 6 is a fragmentary view showing a modified form of wedge in top plan, and

Fig. 7 is a sectional view through a rail plate with the modified form of wedge applied thereto.

The improved tie plate, indicated in general by the numeral 1, is formed of steel or any other desired strong metal and along one side is thickened, as shown at 2, to form a thickened side portion from which projects an inwardly extending flange 3 spaced above the upper surface of the tie plate. The upper face of the plate is shaped to define surfaces 4 and 5, the surface 5 being relatively narrow and extending at a downward incline toward the outer edge of the plate, whereas the surface 4 extends at an incline from its intersection with the inner edge of the surface 5 to the inner edge of the thickened portion 2. Therefore, when a rail 6 is set in place upon the surface 4 with the outer side edge of its base bearing against and extending beneath lugs 7 rising from the base in spaced relation to each other longitudinally of the intersecting edges of the surfaces 4 and 5 the rail will be inclined slightly instead of extending perpendicularly and lean inwardly of a track. This will cause the wheels of a train of cars to rest flat against the upper face of the rail head and prevent the rail head from being worn unevenly and also prevent danger of the wheels jumping the track. A brace 8 rises from the base plate intermediate the lugs 7 and this brace extends inwardly in close contacting engagement with the rail base and terminates in an arm 9 extending upwardly in contacting engagement with the web of the rail with its upper end bearing against the under face of the rail head.

Since the brace is substantially triangular in shape as shown clearly in Figures 1 and 2, the rail will be firmly braced against outward thrust and will be prevented from turning over when subjected to pressure exerted by the wheels of a train of cars.

Openings 11 and 12 are formed through

the tie plates to receive securing spikes 13 and from the under face of the plate extend depending prongs 14, 15 and 16. The prongs 14 and 15 have their inner side faces flush with the outer walls of the openings 11 and 12 and bear against the shanks of the spikes when the spikes are driven into place in order to brace the spikes and cause them to be driven accurately into the tie and the prongs 16 are arranged in a U-shaped path between the openings 11 and 12, as shown in Figure 4, and adapted to be embedded in the tie, as shown in Figure 2, in order to firmly brace the plate and prevent the plate from having movement longitudinally of a tie. By this arrangement the tie plate will be held firmly in place upon a tie when the prongs are embedded in the tie and the spikes driven into place and prevented from having movement either longitudinally or transversely upon a tie.

After the tie plates have been set in place upon ties, the rail is lowered into position and one side portion of the rail base engaged beneath the lugs 7 and brace 8. Abutting rails are properly aligned with each other and spikes may then be driven through the openings 12 in order to hold the tie plates in their proper positions upon the ties. The prongs extending downwardly from the tie plates bite into the tie and the tie plates may be struck with a hammer in order to force these prongs into the ties until the plates rest firmly upon the ties.

In order to firmly hold a rail in place upon each tie plate, there has been provided a wedge or filler 17 which is also formed of strong metal, such as steel. This filler consists of a thick strip which fits into place between the thickened side portion or abutment 2 of the plate and the adjacent side edge of the rail base, and it should be noted that the strip 17 tapers from the end carrying the side arm or head 18 towards its other end. Therefore, the filler when driven into place will fit firmly between the rail base and thickened side portion of the plate and cannot readily slip out of its proper position. The proportions are such that the filler will have a tight wedging fit by the time the head contacts with the edge face of the tie plate. A flange or lip 19 extends from the filler strip for engagement beneath the flange 3 of the tie plate and from the inner side of the filler strip extends a flange 20 which overlaps and rests flat upon the upper face of the rail base. Openings 21 are formed through the filler strip, and it should be noted that these openings are so located that their inner sides open through the inner edge face of the filler strip beneath the flange 20 so that when the filler strip is driven into place and spikes driven through these openings and through the openings 11 into a tie 65 the spikes will bear against the inner side

edge of the rail base. These openings are of greater dimensions than the openings 11, as shown clearly in Figure 3, and, therefore, if the filler strip should expand longitudinally when subjected to heat during summer weather, the spikes will not be damaged. It should also be noted that this enlarging of the openings 21 allows the filler strip to be driven into place until the arm or head 18 bears against the edge face of the tie plate and insures proper registry of the openings 21 with the openings 11. Between the openings 21 and the free side edge of the flange 20 are formed thickened portions 22 which extend at an upward incline from the openings towards their outer edges, as shown in Figure 3, in order to conform to the incline of the under surface of a spike head and allow the spike head to have flat contacting engagement with the thickened portion when driven into place, as shown in Figure 2. Each thickened portion 22 gradually increases in thickness from its intermediate portion towards its ends and then decreases in thickness, as shown clearly in Figures 1 and 3, thereby forming each thickened portion into a seat adapted to snugly receive the head of a spike with portions of the seat rising from opposite sides of the spike head and very effectively preventing the wedge from moving longitudinally out of place after it has been once driven into place and the spikes driven into the tie. Therefore the rails will be very firmly secured upon their plates and the plates firmly held upon the ties. Since the ties are laid two feet apart from center to center and each tie carries one of the improved tie plates, each rail will be very firmly gripped at two feet intervals throughout its length and securely held in place.

In Figures 6 and 7, there has been shown a slightly modified embodiment of the invention. Referring to these Figures, it will be seen that the filler strip 23 is formed with openings 24 to register with the openings 11 of the tie plate and is also formed with seats 25 corresponding to the seats 22 and adapted to receive the heads of spikes driven through the openings 24 and 11 into a tie. This filler strip is also provided with a head 26 corresponding to the head 18 and adapted to bear against a side edge face of the tie plate beneath a rail base. The filler strip is reduced in thickness towards its outer side edge instead of being formed with a lip or flange 19 and the flange 26 projecting from the thickened side portion 2 of the tie plate is gradually reduced in thickness towards its free side edge and extends at an upward incline, as shown in Figure 7, so that it may overlap the 125 filler strip when the filler strip is driven into place. After a tie plate and filler strip constructed as shown in either Figure 2 or Figure 7 has been in use for some time, the inner side edge face of the filler strip against which 130

the side edge of the rail base bears may become worn so that the filler strip does not fit tightly in place or it may be found that when initially applied the filler strip does not fit 5 tightly into place due to inaccuracies occurring when the plates and filler strips are made. In order to prevent the filler strip from being loose when set in place, there has been provided a strand 27 formed of wire. This wire 10 strand is fitted into place beneath the flange 26 or beneath the flange 3 and has its ends bent, as shown at 28, to engage ends of the thickened side portion of the tie plate so that the strand will be prevented from slipping 15 longitudinally out of place when the filler strip is driven into place. By applying this strand a close fit will be established and there will be no danger of the filler strip having longitudinal movement.

Having thus described the invention, I 20 claim:

1. A combined tie plate and rail gripper comprising a plate to rest upon a tie beneath a rail, spike-receiving openings being formed 25 in the plate in spaced relation to the inner side edge of the plate, the inner side edge portion of said plate being thickened to form an upstanding bead disposed between the openings and the inner side edge of the plate 30 and having a lip along its inner edge, abutments spaced inwardly from the outer edge of the plate to bear against a rail set upon the plate, and a filler to rest upon the tie plate between said bead and the inner edge of a 35 rail base with its outer edge portion engaged beneath the lip and its inner edge portion overlapping the rail base, said filler having openings to register with the spike-receiving 40 openings of the plate and at one end formed with a head to bear against an edge face of the plate and limit movement of the filler when driven into place to secure proper registering of the openings in the plate and filler.

2. A combined tie plate and rail gripper 45 comprising a plate to rest upon a tie beneath a rail, spike-receiving openings being formed in the plate in spaced relation to the inner side edge of the plate, a bead along the inner edge portion of said plate, means carried by 50 said plate to engage a rail and brace the rail against outward movement, and a filler to hold the rail in place engaged beneath said lip and having its inner edge portion extended to overlap the rail base, said filler 55 having openings to register with the spike-receiving openings of the plate and adjacent each opening being formed with a seat to receive the head of a spike and prevent movement of the filler when spikes are driven into 60 place through the openings of the filler and plate.

3. A tie plate and rail gripper comprising 65 a plate to rest upon a tie beneath a rail and formed with spike-receiving openings, prongs extending from the under face of the plate to

engage in a tie and hold the plate in place thereon, certain of said prongs being located adjacent the openings and other prongs extending longitudinally of the plate and being spaced from each other longitudinally and transversely of the plate and disposed in substantially a U-shaped path between the spike-receiving openings, the prongs adjacent the 70 openings serving to guide spikes through the openings into a tie and brace the spikes when driven into place, and means to secure a rail upon said plate.

4. A tie plate and rail gripper comprising a plate to rest upon a tie beneath a rail, the plate being formed with spike openings spaced from its inner edge, abutment means carried by said plate to engage a rail and hold the rail against movement towards the outer side of the plate, a bead extending along the inner side edge portion of said plate and having a lip overlying the plate, and a filler strip adapted to be driven into place between said bead and the inner side edge of a rail base and hold the rail firmly against said abutment means, said strip having its outer side edge portion engaged beneath said lip and along its inner side edge being formed with a flange to engage over a rail base, spike 80 openings being formed in said strip to register with the openings in the plate.

5. A tie plate and rail gripper comprising a plate to rest upon a tie beneath a rail, the plate being formed with spike openings spaced from its inner edge, abutment means carried by said plate to engage a rail and hold the rail against movement towards the outer side of the plate, a bead extending along the inner side edge portion of said plate and having a lip overlying the plate, and a filler strip adapted to be driven into place between said bead and the inner side edge of a rail base and hold the rail firmly against said abutment means, said strip having its outer side edge portion engaged beneath said lip and along its inner side edge being formed with a flange to engage over a rail base, spike 90 openings being formed in said strip to register with the openings in the plate.

6. A tie plate and rail gripper comprising a plate to rest upon a tie beneath a rail, the plate being formed with spike openings spaced from its inner edge, abutment means carried by said plate to engage a rail and hold the rail against movement towards the outer side of the plate, a bead extending along the inner side edge portion of said plate and having a lip overlying the plate, and a filler strip adapted to be driven into place between said bead and the inner side edge of a rail base and hold the rail firmly against said abutment 100
